UNITED STATES PATENT OFFICE.

LYNN W. MACOMBER, OF BATTLE CREEK, MICHIGAN, ASSIGNOR, BY MESNE ASSIGNMENTS, TO UNITED STEEL & WIRE COMPANY, OF BATTLE CREEK, MICHIGAN, A CORPORATION OF MICHIGAN.

WIRE BASKET OR RECEPTACLE.

Application filed December 5, 1923. Serial No. 678,652.

To all whom it may concern:

Be it known that I, LYNN W. MACOMBER, citizen of the United States, residing at Battle Creek, county of Calhoun, State of Michigan, have invented certain new and useful Improvements in Wire Baskets or Receptacles, of which the following is a specification.

This invention relates to improvements in wire baskets or receptacles.

The main object of this invention is to provide an improved wire basket or receptacle which may be used for general purposes, display purposes and the like, which is strong and durable and capable of withstanding severe uses, and one which is, at the same time, very economical to produce.

Objects pertaining to details and economies of construction of my improvements will definitely appear from the detailed description to follow.

I accomplish the objects of my invention by the devices and means described in the following specification. The invention is clearly defined and pointed out in the claims.

A structure which is a preferred embodiment of my improvements is clearly illustrated in the accompanying drawing forming a part of this application, in which:

Fig. I is a perspective view of my improved basket or receptacle.

Fig. II is an inverted fragmentary view showing the bottom construction thereof.

In the drawing similar numerals of reference refer to similar parts in both views.

Referring to the drawing, my improved basket comprises a plurality of side hoops 1, a bottom hoop 2 and angled integral slat members 3 formed of folded pieces of wire, the pieces of wire being arranged on the inside of the bottom and side hoops and secured thereto by welding.

The bottom hoop 2 is arranged adjacent the angles of the slat members. The bight ends 4 of the slat members are arranged in overlapping relation so that each slat member overlaps the adjacent member, the overlapping parts being welded together at their crossing point, see Fig. II.

The tie members 5 connect the inner ends of the opposed slat members, these tie mem-

bers closing the openings in the bottom and also strengthening the bottom.

With this arrangement of the slat members the basket is thoroughly braced and may be formed of relatively light wire and, at the same time, is strong and durable.

My improved basket is especially designed by me for display purposes although it may be used for general purposes. When used for display purposes it is preferably used in connection with a display stand as shown in my application for patent filed concurrently herewith.

Having thus described my invention what I claim as new and desire to secure by Letters Patent is:

1. A wire receptacle comprising a plurality of wire side hoops, a wire bottom hoop, angled integral side and bottom slat members formed of folded pieces of wire disposed with their bights at the bottom and welded to said side and bottom hoops, the bottom hoop being disposed adjacent the angles of said slat members, the bight portions of said members being disposed in an annular relation and arranged in overlapping relation so that each overlaps the adjacent members, the overlapping parts of said members being welded together, and tie members connecting the inner ends of opposed slat members.

2. A wire receptacle comprising a plurality of wire side hoops, a wire bottom hoop, angled integral side and bottom slat members formed of folded pieces of wire disposed with their bights at the bottom and welded to said side and bottom hoops, the bottom hoop being disposed adjacent the angles of said slat members, the bight portions of said members being arranged in overlapping relation so that each overlaps the adjacent members, the overlapping parts of said members being welded together.

3. A wire receptacle comprising a plurality of wire side hoops, a wire bottom hoop, angled integral side and bottom slat members formed of folded pieces of wire disposed with their bights at the bottom in an annular overlapping relation and secured together, said slat members being secured to said side and bottom hoops, and tie mem-

bers connecting the inner ends of opposed slat members.

4. A wire receptacle comprising a plurality of wire side hoops, a wire bottom 5 hoop, and angled integral side and bottom slat members formed of folded pieces of wire, disposed with their bights at the bottom and the bight portions of said members

being arranged in overlapping relation so that each overlaps the adjacent members, 10 the overlapping parts of said members being secured together.

In witness whereof, I have hereunto set my hand.

LYNN W. MACOMBER.
